UNITED STATES PATENT OFFICE.

JAMES HARTNESS, OF SPRINGFIELD, VERMONT.

METAL-WORKING MACHINE.

SPECIFICATION forming part of Letters Patent No. 735,254, dated August 4, 1903.

Application filed November 20, 1901. Serial No. 82,993. (No model.)

To all whom it may concern:

Be it known that I, JAMES HARTNESS, of Springfield, in the county of Windsor and State of Vermont, have invented certain new and useful Improvements in Metal-Working Machines, of which the following is a specification.

This invention has relation to lathes and to tools employed in connection therewith; and it has for its object to provide—

First. An opening and closing tool adapted to be operated by fluid-actuated mechanism. Second. An improved tool having a series of variously-formed edges according to the requirements of the work, with mechanism for presenting the said edges to the work in the desired order. In ordinary practice every other tooth of the cutter or tool may be shaped to provide a square shoulder, the other edges being rounded, so that in operation the rounded cutting edge can take a long cut subsequent to the presentation of the next succeeding edge which forms the square shoulder that is usually required.

Third. A tool in combination with improved mechanism for moving the cutting edge and the back-rest into operative relation to the work.

Fourth. A tool having novel means for supplying oil to the portion of the work which is being cut.

Fifth. Improved mechanism with which any number of tools located upon a turret may be brought successively into operative relation.

Referring to the drawings, which illustrate one embodiment of my invention, Figure 1 represents in plan view a portion of a turret-lathe upon which is mounted my improved tool and adjacent to which is secured the tool-closing mechanism. Fig. 2 represents an end elevation of the same with the back-rest and the cutter in inoperative position. Fig. 3 shows the same with the parts in operative position. Fig. 4 represents the same in side elevation. Fig. 5 represents an elevation on the other side, but does not show the turret or the actuating mechanism. Fig. 6 shows the two carriers broken away. Fig. 7 shows the standard or frame. Fig. 8 shows the abutment for the carriers. Fig. 9 shows somewhat conventionally and in perspective

view the cutter having the multiple edges and the means whereby it is rotated step by step. Figs. 10 and 11 show the cutter in detail.

On the drawings, *a* indicates the carriage or slide of a turret-lathe, and *b* is the bed upon which it slides. *c* is the turret, which is mounted upon the carriage and is adapted to be rotated by any suitable means. A lathe having these features is illustrated in my Letters Patent No. 672,398, dated April 16, 1901, to which reference may be had, if desired. The face of the turret is provided with radial grooves, as ordinarily, for the reception of the tools which are bolted thereon. On the turret is placed a tool having a standard *d*. In employing the word "tool" I have used it in the sense of meaning not only the cutter, but also those parts upon which the cutter is mounted, including the standard and the parts attached or secured thereto. The standard has an aperture *d'*, through which the work may be passed, and it is provided with a chamber *d''* for a purpose to be described. To the upper part of the standard or frame are pivoted two carriers *e* and *f*, which are mounted upon fulcrums *e' f'*, respectively, consisting of shodded bolts, as shown in Fig. 3. The carrier *f* depends from its fulcrum *e'*; but the carrier *e* crosses that at *f*, so as to move downwardly as well as laterally, the carrier *f* being cut away, as shown in Fig. 6, to permit free movement of the said carrier *e*. These carriers are arranged on both sides of the work *A* as it projects through the aperture *d'* in the frame or standard *d*, and they are moved to and held yieldingly in inoperative position by a helical spring *g*, which is interposed between them and is placed in sockets *e'' f''*, as shown in Fig. 6.

The carrier *e* is grooved for the reception of the two blocks *h h*, which constitute the back-rest for the work, said blocks being cut away, as at *h'*, to provide a reentrant angle, against the sides of which the work may bear. To adjust said blocks, there are provided the two screws *h''*, which are passed through the carrier and bear against the heels of the blocks. The carrier *f* supports a cutter having multiple cutting edges. This cutter may be formed in any one of a variety of

ways, so that it will be remembered in connection with the following description that so far as many features of the invention are concerned there is no intention on my part to limit the cutter to the particular form which is illustrated. The cutter itself is indicated as a whole at g , and it is formed with a series of teeth having cutting edges g' , g^2 , g^3 , g^4 , g^5 , and g^6 , which may be at different distances from the axis or center. These edges may be formed in any desired way in accordance with the requirements of the work; but, as previously indicated, it is my preference to form every other edge in a curve for turning the work and to form the remainder to produce a square shoulder on the work. The cutter is formed upon an arbor h^4 , which is journaled in the carrier e . The rear portion of the arbor is threaded, as at h^5 , for the reception of a nut h^6 to hold it in place, and it is also formed at its extremity with the ratchet-teeth h^3 , against which bears a leaf-spring i , held between two pins i' i^2 , projecting rearwardly from the carrier e . The teeth of the cutter bear successively against an adjustable pin j , set in a rotatable stud-shaft j' , journaled in the carrier e and held yieldingly against a stop-pin j^2 by a coiled spring j^3 . This pin j withstands the pressure upon the tool due to the operative engagement of the cutting edge with the work, although it is adapted to yield to permit the cutter to be advanced in the direction of the arrow in Fig. 2.

Pivoted upon a screw k passed into the ear k' on the standard d there is a double-ended pawl, one end, k^2 , of which is adapted to engage the ratchet h^3 , while the opposite end, k^3 , is adapted to bear against a pin k^4 , projecting rearwardly from the carrier e . When the carrier is reciprocated laterally away from the work, this pawl engages the pin k^4 and a tooth on the ratchet and rotates the cutter one step, and as the carrier is moved toward the work the end k^2 of the pawl rides over the next tooth of the ratchet in position to operate it. The spring i bears in such way upon the teeth of the ratchet h^3 that it holds the tooth of the cutter, upon which the operative cutting edge is formed, against the end of the pin j .

It is evident that provision must be made to limit the extent to which the carriers may be moved toward the work, and therefore to this end I provide an abutment consisting of a collar m , secured to the lower front portion of the standard by a screw m' . On one side of the collar there is a boss m^2 , having a socket for the reception of the end of an adjusting-screw m^3 , passed through the lower end of the carrier f . The end of the screw m^3 is adapted to play in and out of the socket, but the limit of movement of the carrier is reached when the end of the screw engages the bottom or end wall of the socket. By adjusting the screw, however, the extent of inward movement of the carrier may be varied. On the

opposite side of the collar m is secured a screw-pin m^4 , which extends into an aperture m^5 , formed in the carrier e . The walls of the aperture are partially threaded for the reception of an adjustable screw-pin m^6 , with which the end of the pin m^4 may be engaged when the carrier is moved forward. By the provision of the stops m^2 and m^4 , carried by the single abutment, the pressure of one of the carriers in a measure counterbalances the pressure of the other. I prefer to form the stops in this way, since I thereby prevent the interposition of chips or cuttings between the stops on the carriers and the stationary stops m^2 m^4 , which would prevent the accuracy of operation of the tool.

For the purpose of operating the carriers, I provide fluid-actuated mechanism consisting of two cylinders n o , secured to the carriage a on the front and rear and on the chuck end thereof. These cylinders are slightly inclined from the horizontal, and they are supplied with fluid through the conduits or pipes n' n' and o' o' , respectively. In each cylinder there is a piston n^2 or o^2 , adapted at its inner end to bear against a lever or arm fulcrumed upon the carriage. These arms or levers are indicated at n^3 o^3 , respectively, and they are pivoted upon studs n^4 o^4 , as shown. They are in position to engage the free ends of the carriers and move them to operative position when fluid is admitted to the outer ends of the cylinders n o to effect the advance of the pistons n^2 o^2 . The cylinders, pistons, and arms or levers are so mounted upon the carriage that when the pistons are withdrawn the arms or levers move out of the path of the tools on the turret. They are adapted to coact with a plurality of tools upon the same turret as they are moved successively to position by the rotation of said turret.

The operation of the device is as follows: Assuming that the parts are in the position shown in Fig. 2, fluid is admitted to the rear ends of the cylinders n and o and the pistons are forced inwardly, carrying with them the free ends of the levers n^3 o^3 until the latter engage the free ends of the carriers e and f to swing them about their respective pivots e' f' . The movement of the carrier f is somewhat less than that of the carrier e , so that the back-rest is engaged with the work a short period of time before its engagement by the cutter. The pressure of fluid in the cylinders continues until the end of the cut is reached, when the supply of fluid from the rear end of the cylinder is cut off and fluid is admitted to the front ends thereof to move the pistons in the opposite direction and permit the advancement of the cutter one step. This may occur while the carriage is traveling rearward and before it is again advanced to bring the next cutting edge into engagement with the work.

In order to supply oil or a cooling medium to the cutters and the work, I provide the

chamber d^2 , hereinbefore referred to. Communicating with this chamber is an aperture or port p , so located as to direct a stream of said cooling medium upon the work and the cutter, said port being formed in the upper part of the standard and in the wall of the aperture d' . As shown in Fig. 2, the chamber d^2 communicates with a port p' , which passes through the turret c and which is adapted to register, when the turret comes in proper position, with a chamber p^2 , formed in the carriage. The cooling medium is delivered to this chamber through a pipe p^3 , leading from any convenient source of supply. In the chamber p^2 there is a spring-pressed valve p^4 , which bears against the under surface of the turret and which has a longitudinal aperture therethrough. This aperture is shown in dotted lines, and while closed to prevent the discharge of oil when the turret is turning it is at the same time adapted to register with the port p' in the turret when the latter has reached its working position.

It will be understood that so far as the features of the tool-closing and the back-rest-moving mechanism are concerned I may dispense with the fluid-actuated device and provide mechanical appliances in lieu thereof; that the levers or arms $n^3 o^3$ are not essential to the invention, broadly considered; that the cutter may be varied in form, inasmuch as any other type of multiple edge cutter may be devised to operate upon the work in connection with means for closing upon the work; that the cooling contrivance may be likewise replaced by any other suitable appliance; that the back-rest may be formed integrally with its carrier, and that various of these parts to which I have referred may be used separately or in conjunction with machines and appliances of other kinds, all without departing from the spirit and scope of my invention.

There are numerous advantages to the construction which I have illustrated and described which will be apparent to those skilled in the art to which this invention relates. I call attention to the oscillatory arms intervening between the fluid-operated mechanism and the carriers. By the provision of these arms, which drop clear of the lower end of the tools, the carriers may be moved to operative position as the rocking arms move upward and inward toward the median longitudinal line of the bed. The mechanism for operating the carriers is thus located in such way that it does not cover or obstruct any of the tools upon the turret. I regard the construction and relative arrangement of the carriers as important. It will be observed that they are pivoted upon studs located above the work and are crossed, as described, so that they extend down on opposite sides of the work. The pivot for the cutter-carrier is located above the top edge of the cutting-tool, and there is a surface x on the standard against which the carrier may be seated, and conse-

quently the cutting strain is borne by the stud without a tendency on the part of the carrier to buckle, bend, or twist, the working strains serving merely to throw the cutter-carrier firmly against its seat on the face of the standard. The standard has a similar seat y for the back-rest carrier. This manner of mounting the cutter and back-rest is such that as the center on which the cutter-carrier is pivoted is above the top edge of the cutting-tool the cutting strain amounts to a tensile pull on the part which connects the cutter to its pivot. Comparatively little pressure is therefore required to hold the carrier in operative position. The back-rest must be opposite the edge of the cutter, and hence the best results are secured by crossing its carrier over the cutter-carrier. Moreover, by crossing said carriers a single resetting-spring may be placed between them to operate on both simultaneously.

Having thus explained the nature of the invention and described a way of constructing and using the same, although without attempting to set forth all of the forms in which it may be made or all of the modes of its use, I declare that what I claim is—

1. A lathe having a carriage, a turret rotatable thereon, a tool on said turret having a movable back-rest, and a movable cutter, and independent fluid-operated means mounted on the carriage for moving said back-rest and cutter to operative positions independently of each other. 95
2. A lathe having a carriage, a turret rotatable thereon, a tool on said turret having an oscillatory back-rest carrier, and an oscillatory cutter-carrier, and independent fluid-operated means for moving each of said carriers to operative position independently of the other. 105
3. A lathe having a carriage, a turret thereon, constructed to receive tools having movable cutters and back-rests, and mechanism located on said carriage and adapted to operate successively upon the tools to bring the cutters and the back-rests to operative position. 110
4. A lathe having a carriage, a turret having a cutter and a movable back-rest, and fluid-actuated means mounted partly on said carriage and partly on said turret for moving said back-rest to operative position. 120
5. A lathe having a bed, a carriage, a turret, a tool on said turret having a movable cutter, and a cylinder and piston on said carriage for closing said movable cutter to operative position. 125
6. A lathe having a bed, a carriage, a turret, a tool on said turret having a cutter and a movable back-rest, and a cylinder and piston on said carriage for moving said back-rest to operative position. 130
7. A lathe having a bed, a carriage, a turret, a tool on said turret having a movable cutter, a piston and cylinder on said carriage, and means intervening between said piston

and said cutter for moving the latter to operative position.

8. A lathe having a bed, a carriage, a turret, a tool on said turret having a movable cutter, a piston and cylinder on said carriage and a rocking lever on said carriage for imparting the movement of said piston to said cutter.

9. A lathe having a bed, a carriage, a turret, a tool on said turret having a movable cutter, a piston and cylinder mounted at an inclination on said carriage below the surface of the turret, and a lever for imparting the movement of said piston to said cutter.

10. A lathe having a bed, a carriage, a turret, a tool on said turret having a movable cutter, and means movable upward and toward the median longitudinal line of the bed for moving the cutter to operative position.

11. A lathe having a bed, a carriage, a turret, a tool on said turret having a movable cutter, and means normally located below the path of rotation of the tool as it moves bodily with the turret, for moving said cutter to operative position.

12. A lathe having a bed, a carriage, a turret, a tool on said turret having a movable back-rest and a movable cutter, and pistons and cylinders projecting inwardly toward the median longitudinal line of the bed for moving said back-rest and said cutter to operative position.

13. A lathe having a bed, a carriage, a turret, a tool on said turret having a movable back-rest and a movable cutter, pistons and cylinders projecting inwardly toward the median longitudinal line of the bed for moving said back-rest and said cutter to operative position, and rockers intervening between said piston and said back-rest and said cutter.

14. The combination with a tool having two oppositely-movable elements, to wit: a back-rest and a cutter, an abutment located between said elements, and adjustable stops on said elements for simultaneously engaging said abutment, of means for moving said elements to bring said stops into engagement with said abutment.

15. A lathe-tool comprising a standard, a carrier, a cutter on said carrier having multiple cutting edges, means on said standard for presenting said edges in predetermined order to the work, and a pivoted yielding pin or rest adapted to engage each cutting edge and resist the thrust of the work, the end of said pin or rest being located in the path of the cutting edges.

16. A tool, comprising a standard having provisions for the reception of the work, and having means for attachment to a turret, whereby it may rotate therewith, a bodily-movable cutter-carrier, a cutter thereon, and a pivot located above the operative edge of the cutter for connecting said cutter-carrier to said standard, whereby the strain of said cutter-carrier is longitudinal thereof, said

standard and said carrier having contacting faces so that the strain on the carrier due to the advance of the tool is borne by the said face on the standard.

17. A tool comprising a standard, having means for attachment to a turret, a cutter, a carrier pivoted above the operative edge of the cutter, to the standard, and means for moving said carrier, said standard and said carrier having contacting faces so that the strain on the carrier due to the advance of the tool is borne by the said face on the standard.

18. A tool comprising a standard, having means for attachment to a turret, a cutter, a carrier for said cutter, located transversely of the work, a pivot located above the upper edge of the cutter for connecting said carrier to said standard, and means for moving said carrier above said pivot, said standard and said carrier having contacting faces so that the strain on the carrier due to the advance of the tool is borne by the said face on the standard.

19. A tool comprising a standard having means for attachment to a turret, a bearing-face, a cutter, a cutter-carrier resting against said face, a pivot projecting from said standard for pivotally supporting said carrier, said parts being arranged and combined whereby the working strain on the cutter forces the carrier firmly against the pivot and the said face.

20. A tool comprising a standard, two crossed carriers pivotally connected at their ends to the carrier to depend transversely of the work, a cutter on one carrier, a back-rest on the other carrier, and means for engaging and moving the said carriers.

21. A tool comprising a standard having an aperture for the reception of the work, two pivot-studs located side by side above the work, a carrier pivoted to one stud and extending across one side of the work, a carrier pivoted to the other stud and extending across the first-mentioned carrier and across the other side of the work, a cutter on one carrier, and a back-rest on the other carrier.

22. A tool comprising a standard, a swinging cutter-holder, a swinging back-rest, and means located between them for limiting the movement of the said cutter-holder and the back-rest.

23. A tool comprising a standard, a cutter, a back-rest, crossed carriers pivotally supported upon the standard, and carrying the back-rest and the cutter respectively, means for positively moving said carriers to bring the back-rest and cutter to operative position, and means for moving said carriers in the opposite direction.

In testimony whereof I have affixed my signature in presence of two witnesses.

JAMES HARTNESS.
